UNITED STATES PATENT OFFICE.

JOHN M. PITCHER, OF SUGAR CREEK, HANCOCK COUNTY, INDIANA.

SMOKE-CONSUMER.

SPECIFICATION forming part of Letters Patent No. 350,556, dated October 12, 1886.

Application filed December 16, 1885. Serial No. 185,804. (No model.)

To all whom it may concern:

Be it known that I, JOHN M. PITCHER, of Sugar Creek township, county of Hancock, and State of Indiana, have invented certain new 5 and useful Improvements in Smoke Consumers, of which the following is a specification.

The object of my invention is to provide an improvement on my spark-arrester patented November 17, 1885, No. 330,420, whereby the 10 ashes and cinders are deposited in the ash-pan, and the smoke may be conducted through the grate-bars into the fire-box, thus effecting perfect combustion, thereby securing a great saving in fuel and time usually required in cleaning out the ashes and cinders which accumulate in drums when bituminous coal is burned in furnaces where my jacket is employed, when not provided with my improvement. I accomplish these objects by means of the device 15 described in this specification and illustrated in the drawings filed herewith and made a part hereof, and in which similar letters of reference relate to similar parts of my invention.

In Figure 1, *ip* is an inclined plane, formed 20 by removing a portion of the under side of the jacket or drum *d*, and riveting a section of sheet or boiler iron to the edges of the aperture thus made and to the plate *p*, which forms the back of the fire-box and ash-pan, permitting 25 the lower edge of said section to extend far enough below the bottom of the grate-bars to admit a damper, *do*, of any desired size, to be inserted in the back plate, *p*, between the grate-bars *gb* and inclined plane *ip* thus formed. See 30 Fig. 1, which is a longitudinal section of a boiler provided with my spark-arrester as originally patented, with my improvement applied. Fig. 2 is a cross-section of Fig. 1 on the line *x x*, looking to the right, and Fig. 3 is 35 a cross-section of Fig. 1 at the line *y y*, looking to the left.

In Fig. 1, *do* is a damper loosely hinged to the back plate, *p*, and is opened and closed at will by means of a rod, *r*, provided with notches 40 *r'* near its upper end. This rod is hinged to the lower edge of the damper *do*. *gb* is the grate-bars; *fb*, the fire-box; *b* the boiler, and *d* the drum or jacket; *c*, the smoke-stack; *sp*, the spark-arrester for conducting the smoke and 45 cinders from chamber *bb* to chamber *ch* of my

spark-arrester as originally patented, and to which this invention is to be applied.

The operation of my device is as follows: The ashes and smoke ejected from the flues *fl* into the chamber or smoke-box *bb* are thence 55 driven by the exhaust-steam from the steam-pipe *st* through the spark-arrester *sp* into the chamber *ch*, and thence down the inclined plane *ip*, from whence they can be discharged into the ash-pan through the door or damper 60 *do*, and removed with ease at will. By opening the damper *do* any desired portion of the smoke contained in the chamber *ch* may be admitted into the ash-pan, and a sufficient amount of oxygen admitted through the door 2 to form 65 the proper proportion. The mingled smoke and atmosphere ascend through the grate-bars *gb* into the fire-box *fb*, where all the unconsumed carbon in the smoke is burned up, and perfect combustion thus produced. A little care on the 70 part of the operator in admitting the smoke through damper *do* and the atmosphere through door 2 will be required to effect the desired result; but a few hours' practice will enable any ordinary fireman to operate my device with ease. 75 To further control the volume of smoke, I can, if desirable, apply a damper to the smoke-stack *c*; but in practice I do not find this damper essential. I can also, by reason of my improvement, dispense with the spark-arrest- 80 er by permitting my jacket to communicate directly with the smoke-box *bb*, and placing the exhaust-pipe *st* where it will discharge the exhaust-steam directly into the smoke-stack *c*, when the same result will be attained in a 85 more or less satisfactory manner.

The advantages I derive from employing my device are, first, I can, if desired, dispense with the conductor *sp* by connecting my inclosing jacket directly with the smoke-box *bb* and exhausting the steam into the stack *c*, as above described; second, I can discharge the ashes and cinders into the ash-pan directly, where they can be removed at will with ease; third, I can by means of my device as now improved 95 consume all the carbon usually carried away in smoke, thereby effecting great saving in the cost of constructing my device, the time required to remove the ashes and cinders from jackets not provided with my improvement, 100

and a great saving in the cost of fuel—all objects greatly to be desired.

Having thus described my invention, its objects and advantages, so that any one skilled 5 in the art can construct and operate it, what I claim as new, and desire to secure by Letters Patent, is—

1. A device for conducting smoke from the smoke-box of furnaces through the fire-box, 10 consisting of an inclosing-jacket to envelop the boiler, having an outlet to the smoke-stack, a communication with the smoke-box, and also with the ash-pan, in combination with door *do* and damper *c'*, substantially as set forth.
- 15 2. In a smoke-consumer where an inclosing-jacket for enveloping the boiler is employed, an inclosing-jacket a portion of the under side of which is made to form an inclined plane, *ip*, for conducting ashes and cinders from the

chamber formed by the inclosing-jacket and 20 the outside of the boiler to the ash-pan, substantially as set forth.

3. In combination with a smoke-consumer consisting of an inclosing-jacket, *d*, forming with the outside of a boiler, *b*, the chamber *ch*, 25 communicating with smoke-stack *c*, also with smoke-box *b* through spark-arrester *sp*, and with fire-box *fb* through door *do* and grate-bars *gb*, the damper *c'*, co-operating with door *do* to regulate the amount of smoke passed through 30 the fire-box, substantially as set forth.

In witness whereof I have hereunto set my hand and seal, at Indianapolis, Indiana, this 8th day of December, A. D. 1885.

JOHN M. PITCHER. [L. S.]

In presence of—

ALBERT W. WISHARD,
WM. H. WEBB.
